(57) **CLAIM**

The ornamental design for a flask lid, as shown and described.

DESCRIPTION

FIG. 1 is an upper, front, and left side perspective view of a flask lid showing our new design, showing a drinking portion of the flask lid in a closed position, and in a condition of use with a flask;

FIG. 2 is a top view thereof, with the exemplary flask removed for clarity of details;

FIG. 3 is a bottom view thereof;

FIG. 4 is a left side view thereof;

FIG. 5 is a right side view thereof;

FIG. 6 is a front view thereof;

FIG. 7 is a back view thereof;

FIG. 8 is an upper, front, and left side perspective view of the flask lid thereof, showing the drinking portion of the flask lid in an open position, and in a condition of use with a straw;

FIG. 9 is a top view thereof;

FIG. 10 is a bottom view thereof, with the exemplary straw removed for clarity of details;

FIG. 11 is a left side view thereof;

FIG. 12 is a right side view thereof;

FIG. 13 is a front view thereof; and,

FIG. 14 is a back view thereof.

The broken lines are shown for the purpose of illustrating environmental subject matter and parts of the article that form no part of the claim.

1 Claim, 8 Drawing Sheets
